INSULATED CONTAINER FOR CANNED BEVERAGES OR THE LIKE

Charles W. Bright, 2613 Hutchinson Place, and Harry A. Petersen, 83 Hilltop Drive, both of Titusville, Fla.
32780

Filed Nov. 19, 1968, Ser. No. 14,537

Term of patent 14 years

Int. Cl. D7—99

U.S. Cl. D44—1

FIG. 1

FIG. 2

FIG. 1 is an isometric view of an insulated container for canned beverages or the like showing our new design; with the cover member in partially removed condition;

FIG. 2 is an isometric view with the cover in closed position.

We claim:

The ornamental design for an insulated container for canned beverages or the like, as shown.
